(57) **CLAIM**

We claim, the ornamental design for an ear bud carrying case, as shown and described.

DESCRIPTION

FIG. 1 is a top view of the closed carrying case for the ear buds;

FIG. 2 is an upper front right view thereof;

FIG. 3 is a front side view thereof;

FIG. 4 is a right side view thereof;

FIG. 5 is an upper back view thereof;

FIG. 6 is a bottom view thereof;

FIG. 7 is a lower bottom left view thereof;

FIG. 8 is a top view thereof;

FIG. 9 is an upper right front view thereof;

FIG. 10 is a front side view thereof;

FIG. 11 is a right side view thereof;

FIG. 12 is a top view thereof, the broken lines form no part of the claimed design;

FIG. 13 is an upper front right view thereof;

FIG. 14 is a front side view thereof; and,

FIG. 15 is a right side view thereof.

The broken lines depict environment that forms no part of the claimed design.

1 Claim, 6 Drawing Sheets(56)
